T.J. Woodworth
Mast Supporter
N° 16,510. Patented Jan 27, 1857.

UNITED STATES PATENT OFFICE.

THOMAS J. WOODWORTH, OF SALEM, NEW JERSEY.

SUPPORTING MASTS IN THE DECKS OF VESSELS.

Specification of Letters Patent No. 16,510, dated January 27, 1857.

To all whom it may concern:

Be it known that I, THOMAS J. WOODWORTH, of Salem, in the county of Salem and State of New Jersey, have invented a new and Improved Method of Securing Masts in the Decks of Vessels; and I do hereby declare that the following is a full and exact description thereof, reference being had to the accompanying drawings, and 10 to the letters of reference marked thereon.

The nature of my invention consists in surrounding the mast with a solid "metal" case or "supporter" with an octagonal vertical aperture through the same large enough to admit eight wedges around the mast, which are to be drawn as tight as possible, in order to prevent any motion of the mast in the deck of the vessel, and to secure it in such a manner as to be perfectly 20 water tight without opening the seams of the deck, and at the same time firmly secured in its proper position in the deck. And I hereby declare that the following, is a full, clear, and exact description of the 25 construction and use of the same; reference being had to the annexed drawings making a part of this specification, in which—

Figure 1 is a transverse section; Fig. 2 a longitudinal elevation, Fig. 3 a perspective 30 view, viz:

Letter A represents the mast of a vessel in its proper position in the "supporter"; letter B shows the size and position of the 35 octagonal aperture in which the mast is to be wedged; letter C shows the flange of the "supporter" resting upon the upper surface of the deck of the vessel.

Letters D, D, represent two rabbets on the lower edge of the "supporter" for the purpose of clamping it to its proper place; letter E represents the lower or square portion of the "supporter"; letter F, represents the 40 wedges used in fastening the mast firmly in the "supporter"; and letter G represents a 45 section of the deck of the vessel.

I construct the "supporter" of metal (either of iron or brass) in one solid piece, square on the lower part, which is introduced into the deck in a groove or rabbet so 50 constructed as to retain it firmly in its

proper position; with a circular flange resting on the surface of the deck extending over the square portion far enough to insure a firm foundation, and to make a tight joint between the "supporter" and the deck; and through this "supporter" I leave an octagonal aperture large enough to admit the mast and room for wedging, thus admitting of the mast being wedged in the tightest manner possible without the possibility of in 55 any wise injuring the deck of the vessel or opening the seams thereof, and requiring no canvas or other coating around the mast to prevent it from leaking, thus preventing the mast from decaying, and giving it a firm and substantial support in the deck not liable to leakage or insecurity in any manner.

The "metal support" for the masts of vessels, is so constructed in one solid piece, and so let into and fastened to the deck, that no 60 matter how tightly it shall be wedged no possible injury can result to the deck; preventing any leakage around the mast, and so supporting it as to prevent it from becoming loose by the shrinking of the deck 65 timbers, and from decaying from moisture of the deck as is the case now in the common mode of fastening the mast in wooden partners: leaving no portion of the deck or frame of the same in contact with the mast, but presenting a substantial metal support in close connection therewith of sufficient strength to resist the force of wedging and of a proper size that no leak can arise 70 from the shrinking of the wedges; being an invention of vast utility as must be conceded by all persons acquainted with the present 75 method of securing masts in the deck: as well as much improving the general appearance and finish, substituting in the place of the present unsightly canvas coat, a neat and ornamental improvement on deck.

What I claim as my invention, and desire to secure by Letters Patent, is—

Constructing the partner for the masts of 90 vessels as herein set forth.

THOMAS J. WOODWORTH.

Attest:

JOHN S. HOLLINGSHEAD,

CHARLES F. WOOD.
